UNITED STATES PATENT OFFICE.

THOMAS RIGBY, OF DUMFRIES, SCOTLAND, ASSIGNOR TO WETCARBONIZING LIMITED, OF LONDON, ENGLAND.

UTILIZATION OF PEAT.

1,170,849.

Specification of Letters Patent.

Patented Feb. 8, 1916.

No Drawing.

Application filed July 11, 1914. Serial No. 850,484.

To all whom it may concern:

Be it known that I, THOMAS RIGBY, a subject of the King of Great Britain and Ireland, and a resident of 61 Loretburn street, 5 Dumfries, Scotland, have invented certain new and useful Improvements in and Relating to the Utilization of Peat, of which the following is a specification.

This invention relates to the utilization 10 of peat and in particular by processes of heat treatment thereof such as Ekenberg's wet carbonizing process and recent modifications thereof.

When excavating peat from an undrained 15 or very wet bog we find that as the size of the excavation increases numerous difficulties present themselves. Thus, for a variety of reasons the level of the water in the excavation may vary and render excavation more 20 difficult, or where the excavation is conducted from a floating excavator and the peat fed through a floating pipe line waves may be set up in stormy weather sufficient 25 to damage the pipe line or other gear. In any event the reclamation of the land for 30 agriculture is held up while the deposit is being worked out.

In addition to avoiding the difficulties 35 above indicated the methods described below and in which press effluent from the installation for dewatering the peat is returned to the excavation being worked possess many 40 advantages. Apart from the specific accelerative action of the matters in the effluent 45 on the wet carbonizing reaction when the raw peat mixed with effluent is passed to the factory and the benefits of raised water level in the excavation and of a lowered 50 minimum working temperature in frosty 55 weather due to the warmth of the effluent (a certain amount always remaining therein), there arises the particular benefit that 60 in the event of shortage of water in the particular cell being worked water from the last excavation can be pumped in and in any 65 event the last cell or one or more of them can be used as water store for general purposes.

It will be understood that if the cell walls 70 are sufficiently thick they are for all practical purposes impervious to water and allow of widely different water levels existing in adjacent excavations.

In carrying this invention into effect in 75 connection with a wet carbonizing process,

the peat is gathered by an excavator floating in the water in the excavation, and after maceration pumped through a pipe line floating in the excavation. The gathering is interrupted when the desired dimensions 60 of the excavation have been attained, and work is commenced on a new site to which the excavating plant may be moved by forming a narrow channel to the new site and damming it up when the plant has been floated through. When the succeeding excavation attains the desired dimensions the operation of removal to another site can be 65 repeated and the site thus worked out in the form of a series of cells.

A shortage of water in the cell being worked is more or less overcome by the return of the effluent—some 90% or less of the original water—to the cell and any quantity still required can be made up from one or more adjacent worked out cells. In this way the effluent can be gradually disposed of without danger of nuisance as might occur were it drained away and by appropriate proportioning of the various cuttings it is 80 possible to maintain an adequate make-up water store for the cell under work or for general purposes as well as gradually setting free worked out and empty cells for reclamation. In this way an undulating deposit 85 can be worked out without any danger of loss by drainage or of flooding or any of the other disadvantages referred to.

The intervening walls can when desired be cut away and dealt with in any appropriate manner.

Having now described my invention what I claim as new and desire to secure by Letters Patent is:—

1. A method of gathering and preparing 95 the peat of water logged deposits for fuel consisting in excavating the peat from a particular point, subjecting the excavated peat to heat treatment adapted to render the water more freely expressible, pressing the treated peat to dewater it, changing the region of excavation while the first cutting is still relatively small, effecting a separate and relatively small excavation at another part 100 of the deposit, continuing working out of the deposit in a series of like small and independent excavations and returning to the excavation being worked, water expressed 105 from the heat treated peat; as and for the purposes set forth.

2. A method of gathering and preparing peat to be converted into fuel by heat treatment, consisting in excavating the peat at a particular point, thereupon changing the region of excavation while the cutting is still relatively small, excavating in an adjacent but entirely separate portion of the deposit, so as to result in entirely separate excavations, and adding to the liquid in the working excavation warm effluent expressed from peat which has been subjected to the heat treatment.

3. A method of gathering and preparing peat to be converted into fuel by heat treatment consisting in excavating the peat at a particular point of the peat deposit thereupon changing the region of excavation

while the cutting is still relatively small, excavating in an adjacent but entirely separate portion of the deposit so as to result in 2 a plurality of separate excavations, adding to the liquid in the working excavation effluent expressed from peat which has been subjected to heat treatment and utilizing one of the excavations as a water store to make up shortage as required in the working excavation.

In testimony whereof I have signed my name to this specification in the presence of two subscribing witnesses.

T. RIGBY.
